[57] ABSTRACT

This invention relates to the production of a partition wall of a novel construction due to the use of two novel sections, one of which forms the top and bottom abutments and the frame, while the other forms the framework for the partition wall, the latter being connected to the top and bottom abutments in known manner by means of jacks, work on the site being limited solely to fitting the said jacks and fitting resilient fasteners of a known type which secure the facing panels to the sections.

DEMOUNTABLE PARTITION WALL

This invention relates to the production of a partition wall of a novel construction due to the use of two novel sections, one of which forms the top and bottom abutments and the frame, while the other forms the framework for the partition wall, the latter being connected to the top and bottom abutments in known manner by means of jacks, work on the site being limited solely to fitting the said jacks and fitting resilient fasteners of a known type which secure the facing panels to the sections.

Prior art constructions of partition walls had the disadvantage of not allowing for variations in the dimensions of the main walls and hence requiring adjustment on the site, which resulted in waste of both time and materials, and required skilled labor. Also, the adjustment required prevented re-use, so that such partition walls could not be termed "demountable."

The special section used for the top and bottom abutments and for the frames consists of a U-section, the edges of which are bent inwards and the base of which bears on the floor or ceiling, in the case of the bottom and top abutments respectively. A T extends from the center of each of the arms of the U and the web of the T is perpendicular to the arm of the U, while the crossbar of the T is of a length equal to half the height of the arms of the U, and the two edges of the said crossbar are bent inwards.

The special three-channel section for the partition wall comprises a channel having a horizontal entry for the introduction of the connecting member whereby two sections are twinned, said connecting member being secured by resilient fasteners of a known type; a 35 larger channel having a vertical entry to receive the facing panel, said channel being divided by a vertical partition to form a narrow channel to receive the retaining section for the facing panel concealing the jacks and ensuring continuity as far as the abutment. 40 The three-channel section is used in a twinned arrangement, and an insulating filling can be introduced as indicated hereinbefore by a connecting member which determines the thickness of the partition.

The details of the invention will be apparent from the 45 description with reference to the accompanying drawings.

FIG. 1 is a perspective of the assembly formed by a bottom abutment, a partition wall, and a top abutment, before the fitting of the facing panels which conceal the 50 jacks and provide architectural continuity.

FIG. 2 is a similar perspective view to FIG. 1 but with the spaces between the partition wall and the two abutments being filled in.

FIG. 3 shows the incorporation of glazing at the 55 center of the partition wall, the glazing being secured by glazing beads of a known type.

FIG. 4 is a horizontal section of the corner connection of two partition walls at right angles to one another.

FIG. 5 is a horizontal section of the frame with a hinge clipped on and sealing members of known type.

Referring to FIGS. 1 and 2, the top and bottom abutment members consist of the U-section 1 and the T-sections 2, while the section for the partitioning wall consists of a channel 3 having a horizontal entry for the introduction of the connecting member 14 visible in FIG.

3, by means of which the two sections are twinned; the channel 4 to receive the facing panel 7 and resilient fastening means; the channel 5 to receive retaining sections 6 for the facing panel 8, which conceals the jacks 9; 10, and the insulating filling between the two facing panels 7.

Referring to FIG. 3, the twinned partitioning wall has glazing 11 in the middle, said glazing being fixed by four rubber glazing beads 12 fixed in the channel 4 of the section; the glazing 11 rests on a wooden member 13 which itself bears on the member 14 by means of which the two sections are twinned.

Referring to FIG. 4, the retaining sections 6 are fitted in the channels 5 of the sections to receive the inner facing panels 15 and the outer facing panels 16; the latter are retained at the outer corner by an X-section 17 which allows the facings 16 to be fitted and fixed from the outside of the structure; reference 18 denotes a corner insulating block.

Referring to FIG. 5, the two frame members are formed by the same section as is used for the abutments, the hinge 19 being clipped on to one of the T-sections, the symmetrical channel of the other frame member acting as a bolt for the striking plate 20 of the door 21; reference 22 denotes plastic gaskets of known type. The symmetry of the section enables a double door to be fitted if required.

What I claim is:

1. A demountable wall assembly comprising:
  - a. a top abutment and a bottom abutment, each abutment comprising:
    1. a U-section having the edges of each arm bent inward over a portion of the open end of the U; and
    2. a T-section extending from each arm of the U-section, wherein the web of each T-section is affixed at right angles to a corresponding arm of the U-section, the crossbar of each T-section is equal to approximately one-half of the length of the arm of the U-section, and the edges of the crossbar of the T-section are bent towards the arm of the U-section;
  - b. a wall partition comprising:
    1. two top members and two bottom members, each top member and each bottom member having a first vertical entry channel for receiving a first facing panel, a horizontal entry channel for receiving a connecting means, and a second vertical entry channel for receiving a retaining section which holds a second facing panel;
    2. connecting means for holding together said two top members and for holding together said two bottom members, said connecting means being positioned in said horizontal entry channel of said two top members and of said two bottom members; and
    3. first facing panels positioned in said first vertical entry channels of said two top members and corresponding said first vertical entry channels of said two bottom members;
    - c. retaining sections positioned in said second vertical entry channels;
    - d. first jack means coupling a pair of said top members to said top abutment;
    - e. second jack means coupling a pair of said bottom members to said bottom abutment; and

f. second facing panels positioned to cover said first and second jack means, each said second facing panel positioned between one of said retaining sections and one of said top or bottom members and between a corresponding arm of the U-section and an edge of the crossbar of the T-section, which is bent towards the arm of the U-section.

2. The demountable wall assembly as set forth in claim 1 further comprising insulation between said facing panels.

3. The demountable wall assembly as set forth in claim 2 wherein the spacing between the first facing panels may be varied by varying the length of said con-

necting means.

4. The demountable wall assembly as set forth in claim 1 further comprising a glazing positioned between said two top members and said two bottom members and rubber glazing beads for holding said glazing in position.

5. The demountable wall assembly as set forth in claim 1 further comprising at least one abutment disposed perpendicularly with respect to the top and bottom abutment, said further abutments being connected to said wall partition thereby forming the frame for an opening in said wall partition.
